UNITED STATES PATENT OFFICE.

JOHN H. VAN KLEECK, OF BROOKLYN, NEW YORK.

CLOSURE FOR RECEPTACLES.

No. 806,028.

Specification of Letters Patent.

Patented Nov. 28, 1905.

Application filed August 11, 1905. Serial No. 278,798.

To all whom it may concern:

Be it known that I, JOHN H. VAN KLEECK, a citizen of the United States of America, residing at Brooklyn, in the county of Kings 5 and State of New York, have invented certain new and useful Improvements in Closures for Receptacles, of which the following is a specification, reference being had therein to the accompanying drawings.

This invention relates to certain new and useful improvements in closures for receptacles, and more particularly for bottles.

The invention has for its object the provision of positive and reliable means for effecting a perfect closure of a receptacle, such as a bottle or jar, and in this connection I have devised a closure consisting of a cap and novel means for retaining the cap upon the opening of a bottle or jar. To this end I provide the 15 neck of a bottle or jar with a cam-lock which is actuated to retain a cap upon the opening of the bottle or jar.

The construction entering into my invention will be hereinafter more fully described and 25 then specifically pointed out in the claims, and, referring to the drawings accompanying this application, like numerals of reference designate corresponding parts throughout the several views, in which—

Figure 1 is a fragmentary elevation of a bottle equipped with my improved closure. Fig. 2 is a side elevation of a portion of the neck of a bottle equipped with the closure, the same being illustrated upon a smaller scale 35 than that of Fig. 1. Fig. 3 is a front elevation of the same. Fig. 4 is a vertical sectional view. Fig. 5 is a detail perspective view of a portion of the cam-lock.

In the accompanying drawings I have illustrated the upper end of the neck 1 of a bottle, as an ordinary beverage - bottle, which is 40 slightly enlarged, as at 2, to form the neck of a bottle; also to provide means for securing the closure to the neck of the bottle.

My improved closure is formed of strong 45 and durable pieces of wire which are bent to form a cam-lock. One piece of wire 3 is secured around the neck of the bottle below the collar 2, and pivotally connected to this piece 50 of wire, as at 4 4, is a yoke 5, made of sufficient size to span the top of the neck of the bottle. The cam portion of the lock is clearly illustrated in Fig. 5 of the drawings, where it will be observed that a piece of wire is bent

to form two substantially semicircular arches 55 7 7, a portion of each arch, as designated at 8, serving functionally as a cam-surface. The ends of the piece of wire forming the substantially semicircular arches are bent upon themselves, as at 9 9, and engage the arches, as at 60 10 10, forming segment-shaped slots 11 11 upon coinciding sides of the arches 7 7. Prior to securing the yoke 5 to the neck 1 of the bottle the yoke 5 is passed through the slots 11 11 of the arches, whereby when the yoke 65 has been once secured to the neck of a bottle the piece of wire forming the arches and the slots 11 11 will become a fixture of the bottle. A particular adjunct of the yoke and its 70 apurtenant parts resides in a cap 12, which is 75 preferably made of metal and is adapted to fit over the top of the neck 1 of the bottle. I preferably provide the face of the metallic cap confronting the bottle with a lining of cork 14, which serves to protect the contents of the 75 bottle or receptacle and the metallic cap.

In Figs. 2 to 4, inclusive, I have illustrated the cap 12 as locked upon the neck of the bottle, closing the same. It will be observed that the horizontal portion 15 of the yoke 5 engages the cam-surfaces 8 8 of the arches 7 7 and firmly retains the ends 16 and 17 17 of the arches in engagement with the top of the cap 12. When it is desired to open the bottle or receptacle equipped with my improved 85 closure, the most convenient and simple manner of accomplishing the same is illustrated in Fig. 1 of the drawings. It will be observed that the neck 1 of the bottle having been gripped it is only necessary to press upon 90 the sides of the yoke in order to disengage the ends 16 and 17 17 of the arches 7 7 from the cap 12. As the radius represented by the yoke in vertical position is greater than the radius 95 between the pivotal connection of the yoke and the lower ends of the slots 11 11, a slight pressure upon the yoke will quickly release the ends of the arches 7 7, thus permitting of the cap 12 being removed from the bottle or receptacle.

It is evident from the foregoing that I have devised a simple, strong, and durable and inexpensive closure for receptacles, and it is thought from the foregoing that the construction, operation, and advantages of the herein-described closure will be apparent without further description, and various changes in the form, proportion, and minor details of con-

struction may be made without departing from the spirit of the invention or sacrificing any of the advantages thereof.

What I claim, and desire to secure by Letters Patent, is—

1. The combination with a receptacle, of a yoke pivotally connected to said receptacle adjacent to its opening, a cap adapted to fit over the opening of said receptacle, a piece of wire carried by said yoke, said piece of wire being bent to form two substantially semicircular arches having cam-surfaces against which said yoke is adapted to bear when the receptacle is closed, substantially as described.
2. In a closure for receptacles, the combination with a receptacle having an opening,

of a yoke pivotally connected to said receptacle adjacent to said opening, a cap adapted to fit over said opening, a piece of wire carried by said yoke, said piece of wire being bent to form two substantially semicircular arches having cam-surfaces, said yoke being adapted to bear against said surfaces, and hold the end of said arches in engagement with said cap when said receptacle is closed, substantially as described.

In testimony whereof I affix my signature in the presence of two witnesses.

JOHN H. VAN KLEECK.
